FURNITURE CONSTRUCTION

Donald A. Wallace, New York, N. Y.

Application April 23, 1947, Serial No. 743,324

4 Claims. (Cl. 312—330)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

This invention relates to furniture construction, and more particularly to furniture having a self-sustained skeleton frame carrying individually removable panels which conceal the frame from view.

In furniture, particularly in cabinet or desk-type furniture, of conventional construction, frame members are provided which carry panels, drawers, a top, legs, and other well-known parts of an article of furniture. In that type of construction the designer must take into consideration the appearance of the frame in addition to its structural strength. Also, in furniture construction wherein the frame is visible from the outside, it is necessary to employ a wooden frame in the construction of a wooden item of furniture, as a visible metal frame with wooden panels would generally be considered to present an awkward appearance. This consideration compels the furniture designer to forego the advantages of the great strength and favorable weight-to-strength relationship characteristic of a metal frame. Also, wooden panels connected to a conventional wooden frame are not easily disassembled therefrom; consequently, conventional wooden furniture must be shipped whole as a heavy item.

Military and other personnel whose household goods must stand repeated moves over long distances need items of furniture of sturdy construction and comparatively light weight, but without sacrificing attractiveness of appearance. To answer this need, I have provided a new type of furniture construction utilizing a wholly concealed metal frame carrying individually removable panels which can be disassembled for shipment and reassembled at the place of destination. In case any of the panels are damaged in shipment, replacement panels of standardized size may be substituted for them without impairing the utility or appearance of the article of furniture. The frame itself may be, but need not be, of the knock-down type; while in the following description of a preferred embodiment of my invention I disclose a permanently assembled frame, it will be understood that a knock-down frame whose individual parts are assemblable into a self-sustained structure is suitable for furniture construction in accordance with my invention and thus is within its scope.

Accordingly, one of the objects of my invention

2

is a furniture construction of light weight, great strength, and pleasing appearance, wherein a skeleton frame is wholly concealed by removable panels carried by the frame.

5 Another object of my invention is an article of furniture having panels individually removable from the frame without disturbing other panels carried by the frame.

A further object of my invention is an article 10 of furniture having the appearance of all-wood furniture but having a concealed metal column-and-girder type frame.

A further object of my invention is an article 15 of furniture equipped with drawers slideable in guides carried by a frame which is wholly concealed when the drawers are closed.

Other objects and advantages of my invention 20 will become more fully apparent as the following description of a preferred embodiment thereof proceeds in connection with the appended drawings, wherein:

Fig. 1 is an exploded perspective view of an 25 article of furniture in accordance with my invention;

Fig. 2 is an enlarged section along lines 2—2 of Fig. 1;

Fig. 3 is a sectional view through an upright 30 frame member, taken along lines 3—3 of Fig. 1;

Fig. 4 is a section view of a girder, taken along lines 4—4 of Fig. 1; and

35 Fig. 5 is a front elevation of an assembled furniture cabinet in accordance with my invention.

More particularly, reference numeral 10 denotes a self-sustained skeleton frame, which I prefer to make of metal structural members described hereinafter in greater detail; however, other structural materials, such as wood or plastics, are not excluded from my contemplation. As has been mentioned, frame 10 may be, but need not be, of the knock-down type. It essentially consists of upright members or posts 11, 12, 13, 14, whose top ends are connected by a rectangular arrangement of girders 15, 16, 17, and 18, and whose bottom ends are connected by a

40 rectangular arrangement of girders 19, 20, 21, and 22. Girders 15 to 22 are "angle irons"; which term I wish to be understood to cover all structural materials, whether of iron or not, having two flanges edgewise joined at an angle, as shown in Fig. 4 of the drawings. Upright posts or columns 11 to 14 may likewise be "angle irons"; however, particularly in items of furniture equipped with drawers, I prefer them to be of a somewhat more complex structure, namely, that

45 50 55 of a "channel iron" (which term of course is not

to be understood to be limited to ferrous structural material) having a web 23, a wide flange 24, and a narrow flange 25, as shown in Figure 3 of the drawings.

In addition to the upright members and girder members of frame 10, there are provided horizontal drawer guides 26 of channel cross-section and drawer supports 27, which may be of any suitable cross-section but which I prefer to make of channel cross-section which is characterized by great compressive and shearing strength in relation to its weight. These drawer guides and drawer supports also act as internal braces for frame 10, thus still further increasing its strength.

Top panel 28 is removably connected to the horizontal flanges of girders 15 to 18, e. g., by wood screws (not shown) inserted through spaced perforations in the flanges. Similarly, bottom panel 29 is attached to the horizontal flanges of the bottom girders 19 to 22. Side panels 30 and 31 are suitably connected to the outer faces of upright posts 11 to 14, e. g., by inserting wood screws 32 through spaced perforations in the wide flange 24 of each channel-iron post near its free edge; the narrow width of the other flange 25 affords clearance for the insertion of a screw driver S into the slotted head of the wood screw (see Fig. 2). A back panel 33 may be welded to the webs 23 of rear posts 13 and 14, or attached thereto by wood screws (not shown) or similar conventional attachment means; in the case of a chest of drawers, the back panel serves no specific function, and may be entirely omitted.

In a chest of drawers constructed in accordance with my invention, a number of drawers is provided, each consisting of a bottom 34, back 35, and sides 36, 37. Sides 36, 37 carry runners 38, 39, which slide in drawer guides 26; these drawer guides are carried by the narrow flanges 25 of the upright posts and are disposed out of vertical alignment with the perforations in the wide flanges 24 of the latter, so as to avoid obstruction of these perforations. Each drawer carries a front panel 40 of at least the width of frame 10 and of sufficient height to conceal the vertical frame member (15 or 27) above the drawer; panel 40 is preferably of a material matching that of side panel 30, 31.

Back panel 33 is usually not visible in an article of furniture customarily placed against a wall; consequently, its material is not of importance insofar as the appearance of the assembled article is concerned and in fact may be entirely omitted in a chest of drawers, as has been pointed out. On the other hand, very attractive effects can be accomplished by a furniture designer through the choice of appropriate materials for top panel 28, side panels 30, 31, and front panel or panels 40. This is also true, although to a lesser extent, of bottom panel 29 which is not as plainly in view as the aforementioned panels. Thus, plywood material creates the appearance of an all-wood article of furniture. The front and side panels can be of greatly reduced thickness, as they do not carry any load; this results in a further saving of weight and cost. Plastic materials may also be chosen for the panels with resulting wholly new effects. Each panel is so dimensioned that an edge abuts against the inner face of an adjacent panel to effect complete concealment of the frame (see Fig. 5).

An article of furniture in accordance with my invention may be equipped with legs 41, having flanges 42 attached to the underside of the bottom panel 29. Flanged tapering hollow legs of

circular cross-section, as disclosed in my copending patent application, Serial No. 743,327, "Furniture Leg," filed April 23, 1947 (now Patent No. 2,527,603, issued October 31, 1950), are particularly suitable but are by no means the only ones that may be used in connection with such furniture.

While I have described my new furniture construction in connection with a chest of drawers, it will of course be understood that desks, cabinets with hinged doors, and a great variety of other articles of furniture may be made in accordance with the principles of construction disclosed herein. Modifications of the specific construction of the embodiment disclosed in the above description and appended drawings may of course be readily made by the expert by changes of proportions and structural details without departing from the spirit of my invention, and thus remaining within the scope thereof. I thus intend to claim my invention broadly and to be limited only by the appended claims.

I claim:

1. Furniture comprising a self-sustained skeleton frame having four rigid upright channel-shaped corner members, each of said upright corner members having a web, an inwardly facing narrow flange and an outwardly facing wide flange, a plurality of angled top and bottom girders normal to said upright members and interconnecting the ends of said upright members, a top panel and a bottom panel connected to said girders, the wide flanges of said upright members being provided with a plurality of openings, said openings being disposed near the free edges of said wide flanges and clear of said narrow flanges, side panels removably connected to the outer faces of the wide flanges of said upright members by fastening means extending through said openings, side braces carried by the narrow flanges of said upright members, said side braces being out of vertical alignment with the openings in said wide flanges, and a front panel movably carried by said frame; said top, bottom, side and front panels being normally in abutting relation so as to conceal said frame.

2. Furniture comprising a self-sustained skeleton frame having four rigid channel-shaped upright corner members, each of said upright members having a web, an inwardly facing narrow flange and an outwardly facing wide flange, a plurality of angle-iron top and bottom girders normal to said upright members and interconnecting the ends of said upright members, a top panel and a bottom panel connected to said girders, the wide flanges of said upright members being provided with a plurality of openings, said openings being disposed near the free edges of said wide flanges and clear of said narrow flanges, side panels removably connected to the outer faces of said wide flanges of said upright members by fastening means extending through said openings, front panel supporting means carried by the narrow flanges of said upright members, said supporting means being out of vertical alignment with the openings in said wide flanges, and a front panel movable relative to said frame and carried by said supporting means, said top, bottom, side, and front panels being in abutting relation so as to normally conceal said frame.

3. Furniture comprising a top, a self-sustained skeleton frame having four rigid upright channel-shaped corner posts, each of said posts comprising a web, an inwardly facing narrow flange

and an outwardly facing wide flange, the wide flanges of said corner posts being provided with a plurality of openings, said openings being disposed near the free edges of said wide flanges and clear of said narrow flanges, and top and bottom girders connecting the ends of said posts, individually removable side panels connected to the outer faces of said wide flanges of said posts by fastening means extending through said openings, drawer supports connected to the narrow flanges of said posts, said drawer supports being out of vertical alignment with the openings in said wide flanges, drawers slideable relative to said supports, and front panels carried by said drawers, said top and side and front panels concealing said skeleton frame from an ordinary angle of observation when said drawers are closed.

4. A self-sustained furniture frame comprising four rigid upright channel-shaped corner posts and top and bottom girders connecting the free ends of said corner posts, each of said corner posts comprising a web, an outwardly facing wide flange and an inwardly facing narrow flange, said wide flanges being provided with a

plurality of openings, said openings being disposed near the free edges of said wide flanges and clear of said narrow flanges, and side braces carried by said narrow flanges, said side braces being out of vertical alignment with the openings in said wide flanges; whereby side panels may be removably and interchangeably connected to the outer faces of the wide flanges of said corner posts by fastening means extending through said openings.
